UNITED STATES PATENT OFFICE.

EDMUND LUNKENHEIMER, OF CINCINNATI, OHIO, ASSIGNOR TO THE LUNKENHEIMER BRASS MANUFACTURING COMPANY, OF SAME PLACE.

OIL-CUP.

SPECIFICATION forming part of Letters Patent No. 435,607, dated September 2, 1890.

Application filed March 10, 1890. Serial No. 343,394. (No model.)

To all whom it may concern:

Be it known I, EDMUND LUNKENHEIMER, a citizen of the United States, residing at Cincinnati, in the county of Hamilton and State of Ohio, have invented a certain new and useful Improvement in Oil-Cups, of which the following is a description, reference being had to the accompanying drawings.

In its general appearance and construction my improved oil-cup resembles that shown in reissued Letters Patent No. 10,918, granted me March 15, 1887, my present invention relating principally to a novel method of covering and uncovering the hole through which the cup is filled with oil.

In the drawings, Figure 1 represents a side elevation of my improved cup; Fig. 2, a vertical section through its center; Fig. 3, a top plan view with the valve-stem and binding-nut removed, and Fig. 4 a corresponding view with the top cap turned to uncover the filling-hole.

The body of the cup is composed of a metal base A, having an exteriorly-threaded shank B for attaching the cup to the journal to be oiled, an upper metal cap D, and an interposed glass cylinder C, confined between the cap of the base A and the upper cap D. The base A is provided with an upwardly-extending tube E, whose upper end is threaded exteriorly and projects above the top of the cap D, while its lower end communicates with an outlet-passage F, extending down through the shank B. A valve-stem G, having a lower threaded portion and pointed end and provided at its upper end with a thumb-piece H for turning it, passes down through the tube E. The threaded portion of the stem engages corresponding threads in the lower portion of the tube E, so that the stem may be raised or lowered by turning it, while its pointed end finds a seat in the upper end of the passage F, just below an orifice I opening into the interior of the cup. Suitable packing-rings J are interposed between the ends of the cylinder C and the metal caps, and a binding-nut K, screwed upon the upper threaded end of the tube E, clamps the parts together.

Heretofore, as illustrated in my patent above referred to, the filling-hole L in the upper cap D has been covered and uncovered by a swing-

ing scutcheon journaled on the upper end of the tube E, immediately above and resting on the cap D, and to prevent the movements of said scutcheon being communicated to and loosening the binding-nut K a flat-sided or **D**-washer was interposed between the scutcheon and binding-nut around the tube E, one side of the latter being flattened or cut away to snugly fit the hole in the washer.

My present invention consists in dispensing with both the swinging scutcheon and **D**-washer as heretofore employed. To that end I employ a simple plate M for covering the filling-hole L. This plate is not journaled on the upper end of the tube E, as heretofore, but is rigidly secured to it in any suitable manner, in the present instance by having a flat-sided hole in its inner end which fits the correspondingly-shaped upper end of the tube E in the same manner as a **D**-washer. The filling-hole L is covered and uncovered by turning the top cap D of the cup, and thereby moving the hole under and from under the plate M, the degree of friction against which the cap turns being regulated by the binding-nut K, while the plate M prevents the nut being loosened by the cap. The outer edge of the cap is preferably milled to enable it to be better grasped, and a pin N, coming in contact with the plate M, arrests the turning of the cap when the filling-hole has passed under and is covered by said plate. It will thus be seen that I have simplified the construction of this class of oil-cups by entirely dispensing with one of the separate parts formerly employed in their construction, the plate M taking the place of both the swinging scutcheon and **D**-washer, while the efficiency of the cup and simplicity of its operation are not affected.

My invention is not limited to the particular construction of the cup shown in the drawings, its essential novelty consisting in the combination of the revoluble top with the covering-plate rigidly secured upon the central tube.

Having thus fully described my invention, I claim—

1. In an oil-cup such as described, the combination, with the base A, having the central tube E rigidly mounted thereon, and the revo-

luble cover D, having the filling-orifice L therein, of the covering-plate M, keyed to the central tube E, whereby it is held rigidly with the base A and tube E and its rotation with the revolute cover D in covering and uncovering the filling-orifice L is prevented, substantially as described.

2. In an oil-cup such as described, the combination, with the base A, having the central tube E rigidly mounted thereon with its upper end screw-threaded, the revolute cover

having the filling-orifice therein, and the binding-nut for holding the cover in place, of the covering-plate interposed between the cover and binding-nut and rigidly secured to the central tube, whereby its rotation with the cover and loosening of the binding-nut are prevented, substantially as described.

EDMUND LUNKENHEIMER.
